EDWARD B. HESS, OF NEW YORK, N. Y., ASSIGNOR TO ROYAL TYPEWRITER COMPANY,
OF NEW YORK, N. Y., A CORPORATION OF NEW JERSEY.

TYPE-WRITING MACHINE.

948,974.

Specification of Letters Patent. Patented Feb. 8, 1910.

Application filed April 16, 1909. Serial No. 490,243.

To all whom it may concern:

Be it known that I, EDWARD B. HESS, a citizen of the United States of America, residing in the borough of Manhattan, city, county, and State of New York, have invented certain Improvements in Type-Writing Machines, of which the following is a specification.

This invention relates to adjustable ribbon 10 vibrating mechanism capable of being set to bring opposite the printing point any zone of a plural zone ribbon, and to eliminate the ribbon from the printing operation for stencil work.

15 In some respects this invention in part constitutes an improvement upon my United States Letters Patent No. 874,338 granted December 17, 1907, one of the structures herein shown comprising a link having surfaces of different elevation which is utilized 20 to effect variable movement of the ribbon vibrator.

The invention further relates to adjustable stop mechanism for positively limiting the 25 upward excursions of the ribbon vibrator.

In the accompanying drawings: Figure 1 is a longitudinal vertical section through a typewriting machine disclosing such of the parts thereof as seem desirable for illustration of this invention: Fig. 2, a detail view 30 showing the ribbon vibrator controlling link in a position different from that indicated in Fig. 1: Fig. 3, a like view showing the link in still another position: Fig. 4, a detail 35 view showing a slight modification in construction: Fig. 5, a view similar to Fig. 1 showing the same adjustable means of determining the throw of the ribbon vibrator but a different means for actuating the vibrator, the adjustment being such as to bring 40 the upper zone of the ribbon opposite the printing point: Fig. 6, a detail plan view showing the ribbon vibrator in section and its operating lever in plan: Fig. 7, a view 45 similar to Fig. 5, showing the same construction, the ribbon stop devices being, however, in such position as to permit the lower zone of a two zone ribbon to come opposite the printing point: Fig. 8, is a detail front elevation showing the front plate in which are mounted the ribbon adjusting push-pin buttons marked respectively "Bottom", "Stencil" "Top": Fig. 9, a view similar to Fig. 7 showing the parts adjusted for stencil work; 50 and Fig. 10, a detail sectional view showing

a form of detent device for holding the ribbon vibrator stop devices in any position to which they may be adjusted.

In the several figures 1 indicates the platen, 2 the platen carriage running in ball 60 bearings on a vertically shiftable carriage frame 3. On a centrally disposed projection 4 extending downwardly from the carriage 3 is pivoted at 5, a bell crank lever whose horizontally disposed forwardly projecting 65 arm 6 has hinged to its front end a vertically disposed link 7 (Fig. 1) to which is pinned or hinged at 8 the vertically movable ribbon guide or vibrator 9.

10 indicates an ordinary stationary center 70 guide for the type bar heads. The shorter downwardly extending arm 11 of said bell crank has at its end a lateral projection 12. In rear of the axis 5, the crank has a horizontal projection 13 adapted to contact with 75 an adjustable headed stop screw 14 working in a threaded aperture in the bottom of the carriage 3. The ribbon vibrating bell crank 6, 11, is actuated by a horizontally disposed link 15 suspended by parallel links 16, 17. 80 The link 15 is centrally enlarged and cut out so that one side wall of the opening has three surfaces 18, 19, 20, located at different distances from the respective ends of the link and adapted to engage the lateral projection 12 in the short arm 11 of the ribbon guide actuating bell crank. The link 17 is suspended from a pivotal mounting 21 on a projection on the under face of the carriage 3 and has a forward horizontal projection 22 whose end is connected by a coiled spring 23 with the short arm 11 of the bell crank. The link 16 that supports the front end of the horizontal link 15 is capable of 85 vertical movement such as to bring at will 90 either surface 18, 19 or 20 opposite lateral projection 12 of the bell crank. If a substantially uniform extent of horizontal movement be imparted to link 15, the extent to which the ribbon vibrator is moved 95 will depend upon whether the surface 18 or 20 engages the projection 12 on the bell crank. The surface 19 may be at such distance from the projection 12 when the normal extent of movement is imparted to link 100 15 that there will be no actuation of the ribbon guide. The reaction of spring 23 tends to hold the ribbon guide down and the projection 13 on the bell crank in contact with the stop screw 14 thereby determining the 105 110

normal lowermost position of the ribbon vibrator.

The drawings indicate a key lever machine, 24 being one of the key levers pivoted at its rear end 25 and having its upturned front end equipped with the usual finger piece 26. A link 27 extending up from the key lever engages, between its ends, a horizontally disposed link 28 whose front end 10 is pivoted in a fixed post or support 29. Jointed to the rear end of link 28 is a link 30 hinged at its rear end to the heel of its type bar 31. When the key lever is depressed the type bar will be thrown to the 15 printing point.

32 is an ordinary universal bar disposed below the key levers and carried in the ends of forwardly extending universal bar arms 33 fast upon a rock shaft 34 and having upwardly extending arms 35 to which are applied coiled universal bar springs 36. At the center of the machine there is a similar universal bar arm 37 also fast on the rock shaft 34 and projecting as at 38 in rear 25 thereof. Pivoted at 39 upon such projection is an upwardly extending lever arm 45 having a short forwardly extending arm 40 with a part 41 extending under the universal bar arm 37 and provided with an 30 adjusting screw 42 bearing against the bottom of arm 37. The side of the arm 40 has a slot 43 to receive a headed clamp bolt 44 that screws into the side of the arm 37. This construction affords a ready and accurate means of adjustment of position of 35 the upwardly extending lever arm 45. The extreme upper end 46 of this lever arm is adapted to operate upon a lateral projection 47 on the side of link 15. When a key lever 40 is depressed the universal bar is carried down and the upwardly extending lever arm is thrown forward, its upper end 46 contacting with projection 47 and carrying the link 15 forward. If the adjustment 45 be such as is shown in Fig. 2, surface 20 of the link 15 will operate to actuate the bell crank 6, 11, and there will be imparted to the ribbon guide a definite extent of motion such as to bring opposite the printing point 50 the upper zone of the ribbon. If, as in Fig. 3, the surface 18 is opposite the projection 12 then obviously a greater extent of movement will be imparted to the ribbon guide to bring the lower zone of a double zone 55 ribbon opposite the printing point. If surface 19 of the link is opposite the projection 12, there need not be any movement of the link 15 to actuate the bell crank 6, 11 and consequently the ribbon vibrator will not 60 be moved from its normal inoperative position.

There are provided adjustable stop devices to definitely and positively limit the upward movement of the vibrator, and co-incident 65 with the adjustment of such stop devices the

link 16 is adjusted vertically to determine the relation of link 15 to projection 12 on arm 11 of the ribbon vibrator bell crank. There is a transverse rock shaft 48 mounted in bearings on the under side of carriage 3. 70 At its end adjacent the left hand side of the machine it has a projection 49 to which is connected a link 50 extending forward horizontally and jointed at its front end to a vertically disposed lever 51 pivoted intermediate its ends at 52. Respectively above and below the pivot 52 there are jointed to the lever 51 horizontally disposed push pins, 53, 54, mounted in a plate 55 located in the front plate of the machine. As seen in Fig. 8, 80 these push pins are equipped with finger buttons bearing respectively the words "Bottom" and "Top". Intermediate these two push pins there is a third one 56 having a button or finger piece marked "Stencil". 85 The pin 56 carries on its inner end a plate 57 with a horizontal slot embracing the pivot 52 and having applied to it a coiled spring 58 tending normally to retract it. Projecting laterally from the plate 57 respectively 90 above and below the pivot 52 are pins 59, 60 which, when the push pin 56 is pressed inwardly, brings the lever 51 into vertical position.

The inner end of transverse shaft 48 is at 95 about the center of the machine and on it is a cam-like stop plate 61 having two surfaces of different radius marked respectively a , b , each adapted to co-operate with a projection 6' on the upper edge of the arm 6 of the ribbon vibrator bell crank lever. Also at or adjacent the inner end of the transverse rock shaft 48 is a rearwardly extending projection 62 to which is pivoted the link 16 that supports the front end of the horizontally 100 disposed link 15. The parts are all so related and proportioned that the stop surfaces a , b , are by movement of the rock shaft, brought respectively into proper position to limit movement of arm 6 when the 105 corresponding respective surfaces 18, 20, of link 15 are active. Thus, for stencil work the button marked "Stencil" is pushed in and the parts will be brought into the position indicated in Figs. 1 and 9. In this position a stop for the bell crank is not necessary because the surface 19 of link 15 is so distant from projection 12 that there will be no contact when link 15 is moved endwise. If the push button marked "Bottom" be 110 pressed inwardly the upper end of lever 51 will be rocked rearwardly and link 15 will be adjusted to the position shown in Fig. 3. If the push pin marked "Top" be pressed inwardly, the link will be adjusted to the position shown in Fig. 2. Co-incidently with any such adjustment of the "bottom" and "top" push pins, the proper stop surface a , or b will be brought into position to co-operate with the projection 6' on the arm 6 of 115 120 125 130

the bell crank lever. When printing is to be done from the lower zone of the ribbon, stop surface *b* is set to limit the movement of the vibrator, and when the upper zone of 5. the ribbon is to be used the stop surface *a* is employed. Adjustment of the parts may be such that when the ribbon vibrator has reached the limit of its upward movement the end 46 of lever arm 45 is pressing 10 positively against projection 47, surface 18 or 20 of link 15 is pressed positively against projection 12 of the ribbon vibrator bell crank, and projection 6' on that bell crank is pressed positively against the stop surface 15 *a* or *b*. The same may be true when the adjustment is for stencil work.

It is desirable that there shall be some form of detent device to hold rock shaft 48 in either of the three positions to which it 20 may be adjusted. Such a device of suitable character is shown in the detail sectional view, Fig. 10, which is a section taken in rear of the stop plate 61 as viewed in Figs. 1 and 9. The rock shaft carries a ring 63 having 25 in it three notches adapted to be engaged by a detent ball 64 pressed against the surface of the ring by a coiled spring backed up by an adjustable screw 65 closing the upper end of a threaded aperture in the bottom of the 30 carriage 3.

66 indicates the escapement operating link to be attached to the usual escape lever (not shown). At its front, it is slotted to embrace a projection 67 on the side of a forward projection 68 on the lever arm 45, the parts being so related that at the proper time projection 67 actuates the link. On the side of the escapement link 66 is a lug 69 adapted to be engaged by a part not 35 shown actuated on depression of the space bar also not shown.

In Fig. 4 the end 46 of lever arm 45 is so arranged as to act against the projecting pivot pin 70 by which the rear end of link 45 15 is suspended.

Figs. 5, 7 and 9 show the similar adjustable stop devices, but a different means of actuating the vibrator, similar to that disclosed in my Letters Patent No. 869,854 50 granted Sept. 10, 1907. There is lever arm 71 rocking with the universal bar on depression of the key levers. At its upper end there is a lateral projection 72 that bears against the downwardly extending arm of a 55 ribbon vibrating bell crank 73 overcoming the tension of the bell crank spring 74 and normally holding the ribbon vibrator in its lowermost position. When, however, the arm 71 is rocked forward on depression of 60 the universal bar, the reaction of spring 74 actuates the bell crank which raises the ribbon vibrator. On the side of the arm 71 is another projection 75 that is to be connected with the link (not shown) for operating 65 the escapement devices. With such operat-

ing means it is of course necessary that there should be a stop surface for stencil work and therefore the surface *c*, of greater radius than *a* or *b*, is provided and it is brought into operative position when the center, or stencil, push pin is pressed inward.

In all the main figures of the drawing it is contemplated that the carriage shall shift. In Fig. 7, *d*, *e* indicate the now well known 70 shift links or levers to be appropriately operated from a shift key as is well understood. The stop selecting devices are on the frame and the stop devices, the ribbon vibrator, bell crank, and link 15 are carried 75 by the shifting carriage.

In my application filed November 30th, 1909 Serial Number 530,632 which is a division of my application filed November 15th, 1905 Serial Number 287,489 there is 80 disclosed and claimed ribbon vibrator mechanism wherein the vibrator has imparted to it a plurality of extents of movement, and adjustable coöperating stop devices for limiting the respective movements of the vibrator, and hence such subject matter is not claimed herein, the claims herein being directed to special constructions not disclosed in said application, nor in my applications relating to the same general subject 85 matter viz: application filed May 8th, 1907, Serial Number 372,465, and application filed July 24th, 1907, Serial Number 385,276.

I claim:

1. Ribbon vibrating mechanism for a 100 typewriting machine comprising the combination of a ribbon vibrator, a universal bar, a horizontally disposed endwise movable link having surfaces in different vertical lines, vibrator actuating means operated upon by such surfaces, means for adjusting the link vertically to bring one or another of said surfaces into operative position and means for moving the link endwise on depression of a finger piece.

2. Ribbon vibrating mechanism for a 105 typewriting machine comprising the combination of a ribbon vibrator, a universal bar, a suspended horizontally disposed endwise movable link having surfaces in different vertical lines, vibrator actuating means operated upon by such surfaces, means for adjusting the link vertically to bring one or another of said surfaces into operative position and means for moving the link endwise on depression of a finger piece.

3. Ribbon vibrating mechanism for a 115 typewriting machine comprising the combination of a ribbon vibrator, a universal bar, a horizontally disposed endwise movable link having surfaces in different vertical lines, suspending links supporting said horizontal link, vibrator actuating means operated upon by such surfaces, means for adjusting the link vertically to bring one or 120 125 130

another of said surfaces into operative position and means for moving the link endwise on depression of a finger piece.

4. Ribbon vibrating mechanism for a typewriting machine comprising the combination of a ribbon vibrator, a universal bar, a horizontally disposed endwise movable link having surfaces in different vertical lines, suspending links supporting said horizontal link, vibrator actuating means operated upon by such surfaces, means for adjusting vertically one of the suspending links to bring one or another of said surfaces into operative position and means for 10 moving the link endwise on depression of a finger piece.

5. Ribbon vibrating mechanism for a typewriting machine comprising the combination of a ribbon vibrator, a universal bar, a horizontally disposed endwise movable link having surfaces in different vertical lines, vibrator actuating means operated upon by such surfaces, means for adjusting the link vertically to bring one or another 20 of said surfaces into operative position and means for moving the link endwise on depression of a finger piece, adjustable stop devices limiting the movement of the vibrator operating means and means for co- incidentally adjusting the stop devices and the horizontally disposed link.

6. Ribbon vibrating mechanism for a typewriting machine comprising the combination of a ribbon vibrator, a universal bar, a suspended horizontally disposed endwise movable link having surfaces in different vertical lines, vibrator actuating means operated upon by such surfaces, means for adjusting the link vertically to bring one or another 30 of said surfaces into operative position, means for moving the link endwise on depression of a finger piece, adjustable stop devices limiting the movement of the vibrator operating means and means for co- incidentally adjusting the stop devices and the horizontally disposed link.

7. Ribbon vibrating mechanism for a typewriting machine comprising the combination of a ribbon vibrator, a universal bar, a horizontally disposed endwise movable link having surfaces in different vertical lines, suspending links supporting said horizontal link, vibrator actuating means operated upon by such surfaces, means for adjusting the link vertically to bring one or another of said surfaces into operative position, means for moving the link endwise on depression of a finger piece, adjustable stop devices limiting the movement of the vibrator operating means and means for co- incidentally adjusting the stop devices and the horizontally disposed link.

8. Ribbon vibrating mechanism for a typewriting machine comprising the combination of a ribbon vibrator, a universal bar,

a horizontally disposed endwise movable link having surfaces in different vertical lines, suspending links supporting said horizontal link, vibrator actuating means operated upon by such surfaces, means for adjusting vertically one of the suspending links to bring one or another of said surfaces into operative position, means for moving the link endwise on depression of a finger piece, adjustable stop devices limiting the movement of the vibrator operating means and means for co- incidentally adjusting the stop devices and the horizontally disposed link.

9. Ribbon vibrating mechanism for typewriting machines comprising a ribbon vibrator, its operating bell crank, stop devices for positively limiting the movement of the bell crank and so arresting movement of the vibrator, an adjustable horizontally disposed endwise movable link having surfaces in different vertical plates adapted to positively engage the bell crank to operate it and means acting on the depression of the finger piece to positively move the link endwise.

10. In a typewriting machine, the combination of a shifting carriage frame, a ribbon vibrator, adjustable means mounted on the shifting carriage frame for actuating the ribbon vibrator, adjustable operating means therefor, adjustable stop devices also mounted on the shifting frame for positively limiting the movement of the ribbon vibrator, stop selecting means mounted in the main frame, operative connections between the latter and said stop devices and means whereby said adjustable operating means are adjusted co- incidentally with the adjustment of the stop devices by the selecting means.

11. In a typewriting machine, the combination of a shifting carriage frame, a ribbon vibrator, actuating means therefor mounted on the shifting frame, adjustable operating means for the ribbon vibrator actuating means, a rotative stop device also mounted on the shifting frame and having a plurality of stop surfaces for limiting the movement of the ribbon vibrator, stop surface selecting means on the frame, a link extending therefrom to the rotative stop device whereby the latter may be adjusted and an operative connection between said rotative stop device and said adjustable operating means, and means whereby the latter may be co- incidentally adjusted to impart to the ribbon vibrator the desired extent of movement.

12. In ribbon vibrator mechanism for a typewriting machine, the combination of a shifting carriage frame, a stop device mounted on said frame and having a plurality of stop surfaces acting to limit the movement of the ribbon vibrator, operative connections between said stop device and a lever located in the main frame toward the front of

the machine and a plurality of push pins acting upon said lever to adjust it to different positions thereby co-incidently adjusting the stop devices to bring into operative position the desired stop surface thereof to limit the movement of the vibrator.

13. Ribbon vibrator mechanism for a typewriting machine comprising devices for limiting the movement of the vibrator, said devices having a plurality of stop surfaces either one of which may be brought into operative position, a stop surface selecting device mounted in the main frame and having a plurality of operating push pins on actuation of which the corresponding stop surface is brought into operative position.

14. Ribbon vibrator mechanism for a typewriting machine comprising a ribbon vibrator and a stop device having a plurality of surfaces for limiting the movement of the vibrator, a stop surface selecting device comprising an upright lever and three push pins one of which serves to throw the lever in one direction to bring into position that one of the stop surfaces which permits printing from the upper zone of the ribbon, another of which brings into operation another stop surface which permits printing from the lower zone of the ribbon and the third of which brings the lever into such a position as to permit of stencil work.

15. The combination with a shifting typewriter carriage of a ribbon vibrator, ribbon vibrator stop devices comprising a rock shaft turning in bearings on the carriage and carrying a member having a plurality of stop devices to limit the movement of the ribbon vibrator, and means located in the main frame toward the front of the machine for bringing into operative position the desired stop surface.

16. Ribbon mechanism for typewriting machines comprising the combination of a ribbon vibrator, ribbon vibrator stop devices comprising a rock shaft carrying a member having a plurality of stop devices to limit the movement of the ribbon vibrator, means located in the main frame toward the front of the machine for bringing into operative position the desired stop surface, a ribbon vibrator, its operating bell crank, lever, adjustable bell crank actuating means serving to impart to the bell crank different extents of motion and operative means for adjusting said bell crank actuating means co-incidently with the adjustment of the stop devices.

17. A ribbon mechanism for typewriting machines comprising a ribbon vibrator, its actuating bell crank, a stop device for positively limiting upward movement of the bell crank, a bell crank actuating means positively engaging the bell crank and means operated on depression of the key levers to positively engage the bell crank

operating means whereby at the end of the movement of the bell crank it is positively pressed against its limiting stop by the bell crank actuated means which is positively pressed against it on depression of a printing key lever.

18. A shifting typewriter-carriage combined with a ribbon vibrator mounted on the main frame, an operating-lever therefor pivoted on the carriage, and adjustable operating-lever actuating means suspended from the carriage and adapted to be actuated on depression of character printing keys.

19. A shifting typewriter-carriage combined with a ribbon vibrator mounted on the main frame, an operating-lever therefor pivoted on the carriage, adjustable operating-lever actuating means suspended from the carriage and adapted to be actuated on depression of character printing keys and adjustable stop devices also mounted on the carriage and adapted to limit the movement of the vibrator.

20. A shifting typewriter-carriage combined with a ribbon vibrator mounted on the main frame, its operating-lever mounted on the carriage, adjustable means having surfaces in different planes serving respectively according to the adjustment to engage and actuate said operating-lever, and adjustable stop devices mounted on the carriage and having stop surfaces corresponding respectively with the surfaces of the operating-lever actuating means, whereby when the movement of the vibrator is completed its operating lever is clamped between two of said surfaces.

21. A shifting typewriter-carriage combined with a ribbon vibrator, its operating-lever carried by the carriage, adjustable actuating means for the operating lever, adjustable stop devices for limiting movement of the vibrator, means by which the operator may adjust the stop devices, and an operative connection between the latter and said adjustable actuating means whereby the latter are adjusted co-incidently with the stop devices.

22. A shifting typewriter-carriage combined with a ribbon vibrator, its operating-lever carried by the carriage, adjustable actuating means for the operating lever also carried by the carriage, adjustable stop devices also mounted on the carriage for limiting movement of the vibrator, means mounted on the main frame by which the operator may adjust the stop devices, and an operative connection between the latter and said adjustable actuating means whereby the latter are adjusted co-incidently with the stop devices.

23. A shifting typewriter-carriage combined with a ribbon vibrator mounted in the main frame; its operating-lever pivoted on

- the carriage, adjustable stop devices, for limiting the movement of said operating lever, also mounted on the carriage, a stop selecting device mounted in the main frame, 5 a link connecting it and the adjustable stop devices, adjustable means for actuating said operating lever through different extents of movement and a connection between said means and the adjustable stop devices 10 whereby when the latter are adjusted the former are correspondingly adjusted.
24. Ribbon vibrating mechanism for a typewriting machine comprising the combination of a ribbon vibrator, a universal bar, 15 an endwise movable link having surfaces in different vertical lines, vibrator actuating means operated upon by such surfaces, means for adjusting the link vertically to bring one or another of said surfaces into 20 operative position and means for moving
- the link endwise on depression of a finger piece.
25. Ribbon vibrating mechanism for a typewriting machine comprising the combination of a ribbon vibrator, a universal bar, 25 a pivoted hanging member having surfaces in different vertical lines, vibrator actuating means operated upon by such surfaces, means for adjusting the link vertically to bring one or another of said surfaces into 30 operative position and means for moving the link endwise on depression of a finger piece.

In testimony whereof, I have hereunto subscribed my name.

EDWARD B. HESS.
